UNITED STATES PATENT OFFICE

171,446

LAMP AND COSTUMER COMBINATION

Robert Goldman and Roy R. Nemzer, South Hempstead, N. Y., assignors to Bo-Low Lamp Corp., Brooklyn, N. Y., a corporation of New York

Application June 15, 1953, Serial No. 25,497

Term of patent 7 years

(Cl. D48—20)

To all whom it may concern:

Be it known that we, Robert Goldman and Roy R. Nemzer, both citizens of the United States, and residents of South Hempstead, in the county of Nassau, State of New York, having invented a new, original, and ornamental Design for a Lamp and Costumer Combination, of which the following is a specification, reference being had to the accompanying drawing, forming a part thereof, and of which

Fig. 1 is a front elevational view of a lamp and costumer combination showing our new design;

Fig. 2 is a right side elevational view thereof;

Fig. 3 is a rear elevational view; and

Fig. 4 is a top plan view thereof.

We claim:

The ornamental design for a lamp and costumer combination, as shown.

ROBERT GOLDMAN.
ROY R. NEMZER.
